[57] CLAIM

The ornamental design for a security door stop, as shown and described.

DESCRIPTION

FIG. 1 is a top perspective view of a security door stop showing my new design;

FIG. 2 is a bottom perspective view thereof;

FIG. 3 is a front elevational view thereof, the rear being identical to the front;

FIG. 4 is a top plan view thereof;

FIG. 5 is a bottom view thereof;

FIG. 6 is a side elevational view thereof, the side not shown being identical to the side shown;

FIG. 7 is a reduced top perspective view thereof, with a door and portion of wall being shown in broken lines for illustrative purposes only and forming no part of the claimed design;

FIG. 8 is a top perspective view of an alternate embodiment; and,

FIG. 9 is a bottom perspective view of an alternate embodiment.

FIG. 1

FIG. 2

FIG. 3

FIG. 4

FIG. 5

FIG. 6

FIG. 7

FIG. 8

FIG. 9
